Primary Examiner — Susan Moon Lee(74) *Attorney, Agent, or Firm* — Duane Morris LLP**CLAIM**

I claim the ornamental design for a reader of coded information, as shown and described.

DESCRIPTION

FIG. 1 is a perspective front view of a reader of coded information according to the present invention.

FIG. 2 is a front view of the reader of coded information of FIG. 1.

FIG. 3 is a rear view of the reader of coded information of FIG. 1.

FIG. 4 is a top view of the reader of coded information of FIG. 1.

FIG. 5 is a bottom view of the reader of coded information of FIG. 1.

FIG. 6 is a right side view of the reader of coded information of FIG. 1; and,

FIG. 7 is a left side view of the reader of coded information of FIG. 1.

Broken lines and unshaded portions entirely encompassed in broken line are not claimed.

1 Claim, 7 Drawing Sheets(56)
